UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

KNITTING-MACHINE NEEDLE.

1,178,682.

Specification of Letters Patent. Patented Apr. 11, 1916.

Application filed August 31, 1914. Serial No. 859,348.

To all whom it may concern:

Be it known that I, ROBERT W. SCOTT, a citizen of the United States, and resident of Boston, in the county of Suffolk and State 5 of Massachusetts, have invented certain new and useful Improvements in Knitting-Machine Needles, of which the following is a specification.

The object of my invention is to provide 10 an independently movable needle, of any known type with respect to its yarn engaging parts, with efficient and practical means for frictional engagement with the groove in which it is operated.

15 I am aware of friction devices of the prior art to permit the needles to stand at the point in their grooves attained by the positive thrust of the last cam to actuate them, including such devices as setting an im- 20 pressed lateral bend in the entire shank of the needle, or locally therein. Such structures are objectionable as tending to cause projected needles to occupy a path out of line with their grooves. Other devices with 25 which I am familiar involve the making of special bends or turns in the shank of the wire blank of which the needle is usually, and in the best practice, made. Under conditions of high-speed machines and fine nee- 30 dle gages the durability of the needle and constance of the friction in its groove is a matter of importance, while sharp turns or short impressed bends in the wire blank decrease durability.

35 My new device utilizes a well-known form of high-speed wire blank needle without necessitating any bending of the blank which might injuriously affect its strength.

In the accompanying drawings, Figure 1 40 is a front elevation; and Fig. 2 is a side elevation of a latch needle of a well-known type embodying my new device; Figs. 3 and 4 are respectively similar views of a modified form; Fig. 5 is an elevation of the butt 45 portion of a needle showing another form of the device; Fig. 6 illustrates a hook and spring beard which may be employed with any of the remaining devices; and Fig. 7 is a view similar to Fig. 5 of a further modi- 50 fication.

The shanks 1 of the needles may be formed as usual of a drawn steel wire terminating at their upper ends in the swaged or reduced portion 2, ending in a hook, whether the

needle is of the latch or the spring beard 55 variety. The actuating butt for the needles, at the other end, is formed by a forward bend 3 of the wire blank. The wire of which the needle is made is originally of a size to permit the flattening of the butts 3 60 and the lower end of the shank 4 to the proportions shown, the body of the shank proper 1 and the point section 2 being after- 65 ward reduced to the same lateral dimensions as the butt 3 and the bottom 4. It will be 70 seen that these operations provide the densest and most compressed metal in the structure at the parts 3 and 4, where there is the most strain.

I provide a friction tongue 5 without 75 weakening the remainder of the needle by making a shear cut 6 longitudinally of the enlarged bottom portion 4 of the needle shank. This operation may be performed by dies accurately locating the cut 6, which 80 may be in the plane of the front face of the shank 1. The cutting die may also impress in the friction tongue 5 a bend or convexity such as is shown in Fig. 1, at the same opera- 85 tion; but for some uses I prefer the form shown in Fig. 5 in which the partially de- 90 tached portion 9 of the enlarged lower part of the needle is left straight, but bent at an angle to the plane of the remainder of the needle.

The partially detached portion for the spring tongue may be reduced in thickness, as shown in the drawings, to provide sufficient resiliency. This may be done before or after it is sheared off, and may be effected 90 by milling away a part of the thickness of the area to be separated, or by a swaging operation simultaneous with, before, or after the shearing operation.

For some purposes I prefer to form the 95 tongue in the plane of the shank 1, and in this case the structure may be that shown in Figs. 3 and 4, in which the friction tongue 8 is sheared away from the remainder of the enlargement 4 on the line 7 entering from 100 the bottom of the needle, but leaving a sufficient uncut portion of the enlargement 4 at the top thereof to maintain the strength of the parts. As in the case of the friction tongue 5, the friction tongue may be either 105 curved as shown in Fig. 3, or straight as shown in Fig. 7, but in each case the friction tongue is laterally deflected with respect to

the shank of the needle to engage the side walls of the groove in which the needle plays.

In some cases I may bend the bottom of 5 the needle 4 and the friction tongue symmetrically apart with respect to the central plane of the needles, as shown in Fig. 7.

What I claim is:

1. A knitting machine needle having a 10 butt forming one member of an angular compressed area near one end of the needle, and a friction tongue formed from an excised part of said compressed area and having one end integral therewith.
- 15 2. A knitting machine needle having a butt and shank joining each other at an angle and flat between planes parallel to that of said angle, and having a friction tongue integral with the shank, separated 20 from the adjacent portion thereof by a shear cut, and laterally deflected with respect to the plane of the said angle.
- 25 3. In a needle for knitting machines having a shank and butt formed from a flattened single bend of a wire blank, a friction tongue comprising a portion of the flat wire blank partly sheared away from the remainder and bent at an angle to said remainder.
- 30 4. In a needle for knitting machines, a friction device comprising a flat parallel-

sided integral part of the needle positioned to engage the guiding groove of the usual needle-carrier, said part having therein a split or cut separating a portion of said 35 part from the remainder, said portion being deflected out of line with the remainder of the needle.

5. A knitting machine needle comprising a shank having a solid butt, and a movable 40 tension member extending upwardly above the butt integral therewith and situated in front of the shank.

6. A knitting machine needle comprising a shank having a solid butt, and a flexible 45 tension member extending upwardly above the butt integral therewith and situated in front of the shank.

7. A knitting machine needle comprising a shank having a solid butt, and a tension 50 member extending upwardly above the butt integral therewith and situated in front of the shank and having a portion situated out of the plane of the shank to bear against the wall of the groove of the cylinder. 55

In testimony whereof, I have signed my name to this specification in the presence of two subscribing witnesses.

ROBERT W. SCOTT.
